US0D1067226S

(12) **United States Design Patent** (10) **Patent No.:** **US D1,067,226 S**
(45) **Date of Patent:** **** Mar. 18, 2025**

(54) **AUGMENTED REALITY NECKBAND**

(71) Applicant: **Motorola Mobility LLC**, Wilmington, DE (US)

(72) Inventors: **Marcello Zuffo**, Chicago, IL (US); **Mark D Finney**, Chicago, IL (US); **Michael F Paradise**, Chicago, IL (US)

(73) Assignee: **Motorola Mobility LLC**, Chicago, IL (US)

(**) Term: **15 Years**

(21) Appl. No.: **29/802,124**

(22) Filed: **Aug. 3, 2021**

(51) **LOC (15) Cl.** **14-02**

(52) **U.S. Cl.**

USPC **D14/344**
